CLAIM

The ornamental design for a bottle, as shown and described.

DESCRIPTION

FIG. 1 is a perspective view of a bottle, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof, shown with a first environmental handle; and,

FIG. 9 is another perspective view thereof, shown with a second environmental handle.

The broken lines in the figures illustrate the portions of the bottle and form no part of the claimed design.

The broken line showing of the handles in FIGS. 8 and 9 is for the purpose of illustrating environmental subject matter that forms no part of the claimed design.
